(57) **CLAIM**

The ornamental design for a desk lamp, as shown and described.

DESCRIPTION

FIG. 1 is a front perspective view of a desk lamp;
FIG. 2 is a rear perspective view of the desk lamp;
FIG. 3 is a front elevation view of the desk lamp;
FIG. 4 is a rear elevation view of the desk lamp;
FIG. 5 is a first side elevation view of the desk lamp;
FIG. 6 is a second side elevation view of the desk lamp;
FIG. 7 is a top plan view of the desk lamp; and,
FIG. 8 is a bottom plan view of the desk lamp.
The broken lines as shown in the drawings show portions of
the desk lamp that form no part of the claimed design.

1 Claim, 8 Drawing Sheets(56)
